Silas Hewitt

United States Patent Office.

SILAS HEWIT, OF SENECA FALLS VILLAGE, NEW YORK.

Letters Patent No. 77,374, dated April 28, 1868.

IMPROVED FLOUR-PACKER.

The Schedule referred to in these Letters Patent and making part of the same.

TO ALL WHOM IT MAY CONCERN:

Be it known that I, SILAS HEWIT, of the village of Seneca Falls, in the county of Seneca, and State of New York, have invented a new and useful Improvement in the Mode of Packing Flour, Salt, and like substances, in barrels or casks, for containing the same in a suitable condition for preservation and transport, by mechanical appliances.

The mode heretofore employed to effect this purpose by mechanical means has been by the application of pressure upon the material to be packed, and various devices have been used for pressing the material in the barrel or cask; but it is the case with flour especially, packed by pressure directly upon it, that its quality is deteriorated thereby, and it is never found, on opening a barrel thus packed, in as free and good condition as when first ground, but is often adhered so as to break up in lumps.

In my invention I have adopted the principle frequently employed by manual force to settle together flour and other substances in bags by jolting the bags and contents up and down.

The nature of my invention consists in the practical application of this principle to the larger operation of packing in barrels and casks by mechanical devices, in which application the force produced by the combined weight and motion, or, in other words, the momentum of the several particles of the material, is made active to bring them into closer contact by means of sudden interruptions. This I effect by the mechanism combined and arranged by me for that purpose, which communicates to the barrel or cask containing and receiving the flour or other substance a continued series of movements up and down, which are suddenly arrested at each descent, while the substance is being received therein, and until the operation is completed. Flour thus packed does not adhere together and break up into lumps, but is found, on opening the barrel, as free from adhesion as when first ground.

I have adopted the vertical motion in preference to motion in a lateral or other direction, and the use of a cam-wheel to produce such motion, in preference to other mechanical agents, as being the most simple and effective.

The nature of my invention, therefore, consists in combining a machine in such manner as to practically employ the above-stated principle in packing flour, salt, and other like substances, by mechanism; and I do hereby declare that the following is a full, clear, and exact description of the construction and operation of the same, reference being had to the annexed drawings, making a part of this specification, in which the same letters of reference are used to denote the same parts in each figure, and in which—

Figure 1 is a perspective view,

Figure 2 a longitudinal elevation, and

Figure 3 a longitudinal section of the shaft E and follower D.

A B C is a frame for the machine, (to be used in circumstances where a frame is required.) It may be made of plank and put together as machine-frames usually are. The cross-pieces H and I are firmly secured to the sides A and C, as shown, and may be at any convenient distance apart, and from the top B, which top has a mortise through its centre, (shown at V, fig. 2,) which is about four inches square; and corresponding therewith in a vertical direction, are the mortises m and m^2 through the cross-pieces I and H, which are of like size. The shaft E is of such size as to fit the several mortises V, m, and m^2 , which form guides to preserve its perpendicular direction, but so as to move freely up and down.

I sometimes provide friction-rollers, fixed in the sides of these mortises in the usual manner, one of which is shown at K. I also usually employ a friction-roller set in the lower end of the shaft E, which projects so as to bear upon the cams.

These friction-rollers are not absolutely necessary, and when it is found convenient to dispense with the friction-roller o, in the end of the shaft E, I replace it by a metallic shoe of such shape as to fit the incline of the cams.

The shaft E has the follower D firmly fastened upon it at its upper end, the follower being a flat round

disk, about sixteen inches in diameter, with the shaft at its centre, and at right angles to its lower surface. It may be constructed of wood or metal, but must be of such thickness that when it rests on the top, B, the chines of a barrel resting on the follower will not strike against the top, B. The shaft E is of such length that its lower end, when the follower rests on the top, B, shall reach to within about half an inch of the outer rim of the cam-wheel at the point where that wheel has the least radius, so that it shall not strike the cam-wheel when it falls from the cams.

The driving-shaft P has its bearings R and R². It is about two inches in diameter, and has the fixed pulley N² and the loose pulley n on the projecting end, as shown, and if the machine is to be turned by hand, the crank, W, is fixed on this shaft, as shown.

The cam-wheel G is keyed on the shaft P, at the middle of the distance between the sides A and C of the frame, so as to be directly below the lower end of the shaft E, and the horizontal driving-shaft P is so placed, as to its height, as to give the relative distance between the cam-wheel G at its least radius and the end of the shaft E above stated. The cam-wheel G has two cams, x, opposite each other, which rise on a regular curve from the point where the radius is at least two and a half inches or thereabout to the end of the cam. The greatest radius of the cam-wheel G is about nine inches from the centre, and the least radius about six and a half inches.

To save the labor of separate weighing, and facilitate filling the barrel S with flour or other substance to be packed therein, I combine sometimes the receiver T, constructed in the shape of an inverted truncated cone, suspended by an ordinary scale-beam, which has for its support the standard Z. This receiver has sufficient capacity to contain the full amount required for a single packing, which amount is weighed therein and dropped into the barrel or cask represented at S by means of a valve in its bottom operated by the arm y as fast as required.

The operation of the above-described machine is as follows:

The barrel or cask to be filled and packed has, as is usual, one head taken out; it is first set upright, with the head which remains in the barrel resting on the follower D, and is nearly filled from the receiver T, when the cam-wheel G being set in motion, the cams acting upon the lower end of the shaft E, raise the barrel by the shaft and follower about two inches, and let it fall, the follower stopping upon the top, B, producing a sudden jar in the material contained in the barrel. This occurs twice at each revolution of the cam-wheel, the material being supplied from the receiver until the operation is complete.

I do not claim any of the separate parts of the machine described as new and of my invention.

What I claim as my invention, and desire to secure by Letters Patent, is—

The combination of the weighing-receiver T, provided with its hinged bottom, the vertical shaft E, follower D, and cam G, all constructed, arranged, and operated substantially as and for the purposes herein set forth.

SILAS HEWIT.
